Primary Examiner — Sandra S Snapp*Assistant Examiner* — Ieisha N Price(74) *Attorney, Agent, or Firm* — Muncy, Geissler, Olds & Lowe, P.C.(57) **CLAIM**

The ornamental design for a concrete screw with ring groove, as shown and described.

DESCRIPTION

FIG. 1 is a front elevational view of a concrete screw with ring groove showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a bottom perspective view thereof;

FIG. 8 is a top perspective view thereof; and,

FIG. 9 is a cross-sectional view thereof, taken along line 9-9 of FIG. 5.

1 Claim, 9 Drawing Sheets---
